UNITED STATES PATENT OFFICE.

JOSEPH W. STOWELL, OF TAMARACK, MINNESOTA.

RAIL-JOINT.

1,176,872.

Specification of Letters Patent.

Patented Mar. 28, 1916.

Application filed January 24, 1916. Serial No. 73,929.

To all whom it may concern:

Be it known that I, JOSEPH W. STOWELL, a citizen of the United States, residing at Tamarack, in the county of Aitkin and State 5 of Minnesota, have invented certain new and useful Improvements in Rail-Joints, of which the following is a specification, reference being had to the accompanying drawings.

10 This invention relates to rail joints, and particularly to that type of rail joint wherein the abutting ends of adjacent rails are designed to overlap and interlock with each other.

15 The general object of my invention is to provide a rail joint of this character, so constructed that the rails have interlocking engagement at their abutting ends whereby both of the rails will be depressed equally 20 under load.

A further object of my invention is to provide a construction of this character wherein the rails are detachably interlocked with each other so that they will have unitary longitudinal or lateral movement, and a still further object is to provide a rail joint which does away with the necessity of using fish plates and bolts passing through the webs of the rails.

30 My invention is illustrated in the accompanying drawings, wherein:

Figure 1 is a side elevation of the abutting ends of two rails showing the joint constructed in accordance with my invention; 35 Fig. 2 is a perspective detail view of the end of the rail A; Fig. 3 is a like view of the end of the rail B; Fig. 4 is an under side view of the extremity of the rails A and B; Fig. 5 is a perspective detail view of the locking member 21; Fig. 6 is a top plan view thereof; and Fig. 7 is an end view thereof.

Referring to these drawings, it will be seen that the abutting adjacent ends of the rails A and B are transversely thickened and that 45 the rail A is cut away to provide a portion 11 and the rail B is cut away to provide a portion 10 which overlap each other so that the portion 10 of the rail B will rest upon the portion 11 of the rail A. The rail B is 50 formed at the extremity of the portion 10 with the square tenon 12 which is adapted to be inserted in a square socket 13 or mortise formed in the end of the rail A above the portion 11. On the other end the rail A at 55 the extremity of the portion 11 is formed

with a tenon 14 narrower in width than the portion 10 but having the same height, which is adapted to be received within a socket 15 formed in the end of the rail B below the portion 10, this socket extending inward and 60 opening at its bottom upon the base of the rail. The side walls 16 of this socket 15 are transversely recessed as at 17. This recess 17 extends transversely through the rail and the tenon 14 is formed on its under face with 65 a transversely extending groove or recess 18, which, when the rails are conjoined, registers with the recess 17.

For the purpose of locking the rails in engagement with each other and preventing any 70 longitudinal movement of one rail relative to the other, I provide the locking plate 20 having thereon the upwardly extending rib 21 which is preferably wedge-shaped. This plate 20 is adapted to be held upon a tie by 75 spikes or bolts 22. This plate 20 may either be sunk into the tie or may constitute a wear plate, the other ties supporting the rail being also provided with wear plates 23 so that the rails may be supported at a proper distance above the tie. If the plate 20 is sunk into the tie it is obvious that the rails will 80 rest directly upon the tie.

It will be seen that with this construction the rails are interlocked from any independent, vertical or lateral movement because of the fact that each rail is provided with a tenon which enters a mortise or recess in the other rail and that one rail overlaps the other rail. Preferably the recesses 90 17 and 18 are made slightly dove-tailed in cross section and the rib 21 has the form of a dove-tailed wedge so that when this rib is inserted into the recess 17 it will not only lock the rails from longitudinal movement 95 with relation to each other but it will also act to hold the rails down. Of course the usual spikes may be used upon the base flanges of the rails, but the spikes are not necessary at the joint itself inasmuch as the holding down of the rails is accomplished by the plate 20 and the rib 21. It will be noted also that not only does the extremity of the portion 10 on rail B engage against the end 100 of the wall of the socket 13, but the ends of walls 16 abut against the shoulders 19 formed on each side of the tenon 14.

It will be seen that the rails joined as described cannot possibly get out of alinement, cannot independently rise or fall, and must 110

have unitary movement. It will further be seen that this joint is firmly connected to the tie but may be readily detached therefrom.

Having described my invention, what I claim is:

1. In a rail joint, a rail having a longitudinally extending portion less in height than the rail, the rail rearward of said portion being formed with a longitudinally extending socket, said longitudinally extending portion being formed at its extremity with a tenon having a transverse groove in its under face, an abutting rail having a longitudinally extending portion adapted to overlap the like portion on the first-named rail and formed with a tenon adapted to engage in the socket thereof, the second-named rail having a socket formed in its base to receive the tenon on the first-named rail, the walls of said socket and the base of the rail being formed with a transversely extending recess adapted to register with the recess in the tenon of the other rail, and a locking member adapted to be disposed upon a tie and having a transversely extending rib engaging in said recesses of the socket and tenon and holding the rails locked together.
2. In a rail joint, a rail having a longitudinally extending portion less in height than the rail, the rail rearward of said portion being formed with a longitudinally extending socket, said longitudinally extending portion being formed at its extremity with a tenon having a transverse groove in its under face, an abutting rail having a longitudinally extending portion adapted to overlap the like portion on the first-named rail and formed with a tenon adapted to engage in the socket thereof, the second-named rail having a socket formed in its base to receive the tenon on the first-named rail, the walls of said socket and the base of the rail being formed with a transversely extending recess adapted to register with the recess in the tenon of the other rail, and a locking plate adapted to be supported upon a tie and having a dove-tailed cross section, the recesses being also of dove-tailed form, the rib engaging said recesses locking the rails together and acting to lock the rails to the locking plate.

3. In a rail joint, a rail having a longitudinally extending portion less in height than the rail, the rail rearward of said portion being formed with a longitudinally extending socket, said longitudinally extending portion being formed at its extremity with a tenon having a transverse groove in its under face, an abutting rail having a longitudinally extending portion adapted to overlap the like portion on the first-named rail and formed with a tenon adapted to engage in the socket thereof, the second-named rail having a socket formed in its base to receive the tenon on the first-named rail, the walls of said socket and the base of the rail being formed with a transversely extending recess adapted to register with the recess in the tenon of the other rail, and a locking plate adapted to be supported upon a tie and having a dove-tailed cross section, the recesses being also of dove-tailed form, the rib engaging said recesses locking the rails together and acting to lock the rails to the locking plate.

4. The combination with a rail having a dove-tailed recess extending transversely across the under face of its base, of a plate adapted to be engaged with a tie and having a dove-tailed rib upon its upper face interlocking with said recess to thereby lock the rail to the tie, the plate constituting the sole means whereby the rail is held to the tie.

5. The combination with a rail, of a plate upon which the rail is adapted to be supported, said plate being adapted to be engaged with a tie, the plate and rail having one a dove-tailed rib extending transversely across it and the other a dove-tailed recess into which the rib engages and interlocks to thereby lock the rail to the plate, the dove-tailed rib and recess tapering longitudinally.

In testimony whereof I hereunto affix my signature in the presence of two witnesses.

JOSEPH W. STOWELL.
